SEALING MECHANISM

Leon Benoit, New York, N. Y., and Clifford C. Moth, Tenafly, N. J.; said Moth assignor to said Benoit

Application June 8, 1936, Serial No. 84,152

5 Claims. (Cl. 216—29)

The device of the present invention in the form shown is particularly designed for use in conjunction with a carton closing machine of the type illustrated in a copending application, Serial No. 81,208, filed May 22, 1936, although the present sealing mechanism may be otherwise employed, either in conjunction with carton closing mechanism or for the purpose of sealing cartons closed by hand, or for the application of stamps, 10 seals or the like, to cartons, boxes, or other objects generally.

The mechanism is designed primarily to seal the cover flaps of an egg carton which is so constructed as to provide a carton body having side 15 walls each terminating in a cover flap adapted to be folded inwardly and downwardly to overlie the carton body. Each of the cover flaps terminates in a marginal tucking flap, and when closed the two tucking flaps extend downwardly 20 in vertical relation to the carton body and in contact with one another along the longitudinal center partition which is afforded by folding the carton body along the longitudinal center. The carton body itself affords two trough-shaped 25 compartments which are divided into cells by the provision of vertical cross partitions which are entered through slots in the trough-shaped divisions of the body with which they interlock. The bases of the cross partitions extend below 30 the body walls and furnish the base upon which the carton is supported, and the cross partitions also afford cross abutments for actuating the feeding mechanism of the present sealing apparatus in the manner to be hereafter described.

35 The sealing machine is designed to be actuated by the passage of each carton in a procession of filled cartons and to feed downwardly a section of gummed tape from a roll and to sever the section and apply the same to the joint or seam afforded between the turned down tucking flaps, the arrangement being such that each carton upon its arrival will initiate and complete the 40 cycle of sealing operations, after which the sealing mechanism will stand idle until the arrival 45 of the next succeeding carton.

The invention also includes means for restoring the sealing mechanism to its normal idle position in the event that it should get out of step 50 for any reason, which is a highly desirable feature in order to insure the application of the seals uniformly to the intended position upon the carton. The invention also includes means for moistening the adhesive and for regulating 55 the supply of water to the moistening bath for

application through a strip of wicking to the gummed surface of the tape.

The invention is also directed to the correlating and timing of the mechanisms provided for feeding, cutting and applying the severed sealing strips so that the sealing operations will proceed accurately, uniformly and rapidly, irrespective of the speed with which the cartons are delivered.

Further objects and details will appear from a description of the invention in conjunction with the accompanying drawings, wherein,—

Figure 1 is a side elevation of the invention showing the same mounted upon the terminus of a carton closing machine of the character described in the copending application above referred to;

Fig. 2 is an end elevation of the same looking inwardly toward the sealing mechanism from the discharge end and toward the procession of oncoming cartons;

Fig. 3 is a detail of the star wheel and the restoring device for resetting the same in the event it gets out of step;

Fig. 4 is a similar view showing the parts in a different operative position;

Fig. 5 is a detail taken on line 5 of Fig. 2 showing the presser roller for exerting pressure upon the sealing strip applied to the carton;

Fig. 6 is a sectional elevation through the center of the sealing mechanism; and

Fig. 7 is a detail showing the cutting knife and associated parts for operating the same.

The sealing mechanism of the present invention is mounted at the terminus of the closing machine and is suitably supported upon bed plates 10, 10 which stand in spaced relation to one another and project outwardly beyond the framework 11 of the closing machine, although the sealing mechanism might obviously be supported in any suitable or convenient manner.

The cartons are fed to the sealing machine by means of an endless chain conveyor 12 having outstanding teeth or lugs 13, which in the present instance are suitably spaced to act upon alternate cross partitions 14 of the cartons. The cartons rest upon suitably driven conveyor belts 15 so that the advance of the cartons will be occasioned by the positive action of the teeth or lugs 13 supplemented by the conveying action of the belts 15. The conveyor chain 12 passes 50 around a sprocket wheel 16 which is power driven either directly or through the mediation of the sprocket chain 12. The bed plates 10 are suitably spaced to permit the teeth or lugs 13 on the upper turn of the conveyor chain 12 to pro- 55

ject upwardly in position to engage the cross walls 14, and immediately in advance of the sprocket 16 is located a star wheel 17 having seven teeth 18 so spaced as to be engaged by the seven cross partitions 14 of the carton.

It will be noted from Fig. 2 that the carton is provided with a body 19 which is bent or folded to furnish two trough-shaped channels separated by a center partition 20 and that the cover flaps 21 are each provided with a marginal tucking flap 22 which are tucked downwardly into the carton body within the space adjacent to the longitudinal partition 20. The configuration is one which permits the exposed centers of the cross partitions 14 to engage the teeth of the star wheel and impart the necessary motion thereto to actuate the sealing mechanisms now to be described.

The star wheel 17 is mounted upon a shaft 23 journaled within brackets 24 hung from the bed plates 10. The bed plates furnish a support for spaced standards 25, which constitute the frame for the sealing mechanism. The standards at their outer ends 26 are bifurcated to afford mountings for the reduced ends 27 of a spindle 28 which carries a spool 29 upon which is mounted a roll 30 of adherent tape. The roll is supported upon a pair of rollers 31 journaled at the ends of cross arms 32 on the standards and suitably spaced to support the tape roll 30 so that as the roll is depleted the spindle 28 will work downwardly through the slotted ends 26 without interfering with the feeding of the strip from the roll.

The strip is carried outwardly around a guide rail 33 and along the surface of an inclined guide plate 34, and through the bite of a feed roll 35 and a serrated idle presser roll 36, which roll is mounted upon a shaft 37 carried by spring bars 38, each of which at its upper end is secured to a block 39 supported by the guide plate 34. The blocks 39 also afford a mounting for shoulder screws 40 which pivot a swinging yoke 41 of inverted U-formation having side arms 42 and an inverted cross head 43 carrying a serrated knife 44 which operates through a cross slot 45 in the guide plate 34. The blocks afford a mounting for a guide bar 40a under which the strip is carried. The guide plate is also provided with an aperture 46 through which the surface of the feed roll 35 projects, and immediately below the cutting aperture 45 is located a cross guide bar 47 which serves to hold the sealing strip in position against the surface of the guide plate 34. The lower end of the sealing strip is carried beneath a presser roll 48 which is positioned to press down the severed strip section upon the surface of the carton. Before delivery to the carton, however, the gummed strip is moistened by contact with the outwardly projecting end of a swab of wicking 49, which is moistened in a manner presently to be described.

The feed roll 35 and the knife 44 are both positively actuated through transmission mechanism 65 in train with the star wheel shaft 23. The means for actuating the knife comprises a cam 50 having a maximum elevation 51 and an abrupt shoulder 52. The cam bears upon a roller 53 carried by an arm 54 which is slotted at its lower end 55 to embrace the shaft 23. The upper end of the arm 54 is pivoted to a bracket arm 56 carried by the swinging yoke 41, and the arm is drawn inwardly by the action of a spring 57. This arrangement affords a sudden cutting movement to the knife as the shoulder 52 of the cam

50 passes under the roller 53 and the spring 57 draws the arm 54 forward to release the knife.

The star wheel shaft 23 at its opposite end carries a cam 58 operating upon a roller 59 carried by an arm 60 slotted at its lower end 61 to embrace the shaft 23. The upper end of the arm 60 is pivoted to a swinging arm 62 freely mounted upon a shaft 63 to which the feed roll 35 is keyed. The shaft is provided with a ratchet wheel 64 coacting with a dog 65 pivoted upon the end of the swinging arm 62 and spring pressed to engage the teeth of the ratchet 64 for imparting a limited rotation to the shaft 63. The arm 60 acts against the tension of a spring 66.

The cam 58 in its relation to the swing of the arm 62 is computed to gradually feed forward the gummed section of the intended length in advance of the release of the knife 44, and thereafter, upon the restoration of the knife, to continue the feeding operation sufficiently to bring the terminus of the gummed strip beneath the guide rod 47 in preparation for the next succeeding feeding and cutting operation.

The wicking swab 49 projects outwardly through the forward wall 67 of a tank 68 having a well 69. The wicking is supported upon an inclined plate 70, and the well receives the lower end of a supply pipe 71 which at its upper end receives the inverted mouth of a globe shaped bottle 72 carried by a suitable holder 73, the bottle being held in place by a spring arm 74. The arrangement is one which limits the feeding from the bottle, which constitutes a reserve reservoir, since the feeding will cease as soon as the water level rises sufficiently to immerse the discharge end of the tube 71, thereby preventing ingress of air upwardly into the bottle. The inner end of the wicking swab is thus immersed to the intended degree to draw up the amount of moisture necessary to moisten the gummed strip as it is carried downwardly in contact with the end of the wicking swab.

The roller 48 is carried by arms 75 projecting inwardly from a cross rod 76 carried by standards 77. The rod has mounted thereon a yoke 78 having a finger 79 which embraces a pin 80 projecting from one of the standards 77, which pin mounts a spring 81 adapted to be regulated by lock nuts 82, the arrangement being such as to positively limit the down swinging movement of the yoke 78 and thus limit the downward pressure of the roller 48. The upward movement will be resisted by the spring 81 which when properly adjusted serves to impart the desired pressure to the severed section of the sealing strip to seal the same upon the carton as the latter passes beneath the roller 48.

If by any chance the strip feeding mechanism should get out of step with the advance of the cartons, unless corrected this would have the effect of applying the seal at the wrong point on the carton, and provision is made to correct such possible mal-adjustment of the parts by the means now to be described.

The star wheel shaft 23 has keyed thereon a mutilated ratchet wheel 83 having at one point in its periphery a plane section 84. The ratchet wheel coacts with a dog 85 carried by a swinging arm 86 loosely mounted on the shaft, the dog being held in engagement with the ratchet teeth by a spring 87. The swinging arm 86 has pivoted thereto a rocking arm 88 which is slotted at its opposite end 89 to embrace the shaft 90 which carries the conveyor sprocket 16 and which is constantly driven at uniform speed during the 75

operation of the machine. The shaft 90 has keyed thereon a star shaped cam 91 having, as shown, four rounded arms 92 which bear against a roller 93 on the rocking arm 88 and serve to 5 advance the arm against the tension of a spring 94.

The projection of the ratchet teeth is such as to permit them to slip past the dog 85 during the normal rotation of the star wheel 17 when 10 carried around by the advance of the carton. If the star wheel and associated parts are properly in step, the final passage of the carton will bring the plane section 84 of the ratchet wheel around to the point of contact with the dog 85, so that 15 the latter will reciprocate idly upon the plane surface thus presented. If, however, the passage of the carton should leave the star wheel and associated parts out of proper position with relation to the coacting cartons, a toothed portion 20 of the ratchet wheel 83 will be presented to the dog 85, so that the reciprocation of the dog will turn the star wheel shaft 23 to the degree necessary to bring the plane section around to the dog and thus restore the parts to their intended position 25 so that the next succeeding carton will feed and apply the seal at the intended point.

By the provision of the restoring mechanism, therefore, the operation of the star wheel is so regulated that it will always be set to uniform 30 position in advance of the arrival of an oncoming carton. During the passage of a carton, the dog 85 in engagement with a ratchet tooth will, on its active movements, follow the tooth around at the same rate of travel, and on its return 35 movements will slip idly over the ratchet teeth, so that the dog only becomes functionally active in case the ratchet wheel should stop rotating at a point at which the dog engages a ratchet tooth during its active swing, in which event it will im- 40 part a restoring movement to the shaft 23 in the amount required to bring the shaft around to its normal position.

Operation

45 The operation of the device may be briefly summarized as follows: The filled cartons will be positively advanced to the sealing position by the engagement of the teeth or lugs 13 with the cross partitions of the carton, assisted by the carrier belts 15 upon which the base of the carton rests. During such advancement the alternate cross partitions of the carton will encounter the teeth of the star wheel and impart a definite or computed degree of rotation to the star wheel shaft. 50 This turns the cams 51 and 59 to the degree required to first feed down a section of the gummed strip of the intended length and thereafter suddenly release the knife or cutter 44 which severs the sealing section from the remainder of the strip.

60 During the down feeding of the strip it will be moistened by the wicking swab 49 and its leading edge will be brought into contact with the top surface of the advancing carton, thereby causing an adherent contact to be established at the instant the gummed sealing section passes under the roll 48. At this instant the knife will descend and sever the section, which will thus be drawn down by the advancement of the carton and press 65 down onto the surface to effect the sealing operation. After the knife has been withdrawn, the feeding of the main sealing strip will continue slightly until its leading edge has been brought beneath the guide rod 47, which concludes the 70 operations performed by the mechanism, after 75

which the sealed carton passes to the discharge end of the machine and is removed.

By utilizing the carton itself as the means for actuating the sealing mechanism, and by providing means to effect a restoration of the parts to 5 normal position in the event of mal-adjustment, an accurate sealing of the cartons can be secured at all times irrespective of the speed of arrival or the speed of passage through the machine.

10 Although the mechanism has been described with particular reference to the sealing of a carton having cross partitions of the character shown, it is not the intention to limit the invention in any way to the sealing of cartons of this 15 particular character, since the mechanism can be employed for the application of seals, stamps, or other gummed stickers, to boxes or other articles adapted to be fed through the machine, particularly when the same are adapted, by reason of 20 their configuration, to initiate the train of operations required in feeding, moistening, cutting and applying the seals to the objects thus fed through the machine, so that, unless otherwise indicated, it will be understood that in referring to cartons 25 we have in mind other forms of receptacles or objects having the required form or configuration to be acted upon in accordance with the principles of the present invention.

We claim:

1. In a sealing mechanism, the combination of 30 means for advancing an object to be sealed, means for supporting an adhesive strip, devices for feeding a predetermined section of said strip to the object to be sealed with each actuation of the 35 mechanism, a moistening device located at a point between the feeding devices and the means for advancing the object for supplying moisture to a previously unmoistened section of the strip during its advancement to the sealing position, means 40 for severing the advanced section at a point between the feeding and moistening devices, a member adapted to be engaged and have motion imparted thereto by the passage of an object to be 45 sealed, and mechanisms operated by power imparted by said moving member for actuating the strip feeding and severing devices in timed relation to feed the leading end of the strip to a position to secure adherent contact with the advancing object before the severing mechanisms are 50 actuated and to thereafter again feed the leading edge of the unsevered strip to a position below the severing devices in preparation for the next cycle of operations.

2. In a sealing mechanism, the combination of 55 means for advancing an object to be sealed, means for supporting an adhesive strip, devices for feeding a predetermined section of said strip to the object to be sealed with each actuation of the mechanism, a moistening device located between 60 the feeding devices and the means for advancing the object for supplying moisture to a previously unmoistened section of the strip during its advancement to the sealing position, means for severing the advanced section at a point between 65 the feeding and moistening devices, a rotatably mounted member adapted to be engaged by the passage of an object to be sealed, and mechanisms in train therewith and adapted to be operated by the rotation thereof for imparting feeding and 70 severing movements to the feeding and severing mechanisms in timed relation to feed the leading end of the strip to a position to secure adherent contact with the advancing object before the severing mechanisms are actuated.

3. In a sealing mechanism, the combination of means for advancing an object to be sealed, means for supporting an adhesive strip, devices for feeding a predetermined section of said strip to the object to be sealed with each actuation of the mechanism, a moistening device located between the feeding devices and the means for advancing the object for supplying moisture to a previously unmoistened section of the strip during its advancement to the sealing position, means for severing the advanced section at a point between the feeding and moistening devices, a rotatable star wheel having teeth adapted to be engaged by the object being sealed, cams operated by the rotation of the star wheel, and connections between said cams and the strip feeding and severing mechanisms respectively for operating said mechanisms by movements imparted to the star wheel and in timed relation to feed the leading end of the strip to a position to secure adherent contact with the advancing object before the severing mechanisms are actuated.

4. In a sealing mechanism, the combination of means for advancing an object to be sealed, means for supporting an adhesive strip, devices for feeding a predetermined section of said strip to the object to be sealed with each actuation of the mechanism, a moistening device located between the feeding devices and the means for advancing the object for supplying moisture to a previously unmoistened section of the strip during its advancement to the sealing position, means for severing the advanced section at a point between the feeding and moistening devices, a rotatable star wheel having teeth adapted to be engaged by the object being sealed, cams operated by the rotation of the star wheel, connections between said cams and the strip feeding and severing mechanisms respectively for operating said mechanisms by movements imparted to the star wheel and in timed relation to feed the leading end of the strip to a position to secure adherent contact with the advancing object before the severing mechanisms are actuated, a restoring mechanism comprising a rocking arm and means for imparting constant rocking movements thereto, a dog actuated by the rocking arm, and a ratchet having fixed relation to the star wheel and provided with a smooth section adapted to permit idle reciprocation of the dog when the star wheel stands in normal position and to permit effective engagement between the dog and the ratchet to occur when the star wheel gets out of its intended step with the objects to be sealed.

ing end of the strip to a position to secure adherent contact with the advancing object before the severing mechanisms are actuated, and constantly actuated restoring mechanisms adapted to restore the star wheel to normal position in the event of mal-adjustment.

5. In a sealing mechanism, the combination of means for advancing an object to be sealed, means for supporting an adhesive strip, devices for feeding a predetermined section of said strip to the object to be sealed with each actuation of the mechanism, a moistening device located between the feeding devices and the means for advancing the object for supplying moisture to a previously unmoistened section of the strip during its advancement to the sealing position, means for severing the advanced section at a point between the feeding and moistening devices, a rotatable star wheel having teeth adapted to be engaged by the object being sealed, cams operated by the rotation of the star wheel, connections between said cams and the strip feeding and severing mechanisms respectively for operating said mechanisms by movements imparted to the star wheel and in timed relation to feed the leading end of the strip to a position to secure adherent contact with the advancing object before the severing mechanisms are actuated, a restoring mechanism comprising a rocking arm and means for imparting constant rocking movements thereto, a dog actuated by the rocking arm, and a ratchet having fixed relation to the star wheel and provided with a smooth section adapted to permit idle reciprocation of the dog when the star wheel stands in normal position and to permit effective engagement between the dog and the ratchet to occur when the star wheel gets out of its intended step with the objects to be sealed.

LEON BENOIT.
CLIFFORD C. MOTH.
